UNITED STATES PATENT OFFICE.

ANDREW HELDRICH, OF PHILADELPHIA, PENNSYLVANIA, ASSIGNOR TO MULTIPLEX SALES REGISTER COMPANY, OF LOUISVILLE, KENTUCKY, A CORPORATION OF KENTUCKY.

AUTOGRAPHIC REGISTER.

1,216,312.

Specification of Letters Patent. Patented Feb. 20, 1917.

Application filed January 7, 1916. Serial No. 70,833.

To all whom it may concern:

Be it known that I, ANDREW HELDRICH, a citizen of the United States, resident of Philadelphia, in the county of Philadelphia and State of Pennsylvania, have made a certain new and useful Invention in Auto-graphic Registers; and I declare the following to be a full, clear, and exact description of the same, such as will enable others skilled in the art to which it appertains to make and use the invention, reference being had to the accompanying drawings, and to letters or figures of reference marked thereon, which form a part of this specification.

- 15 Figure 1 is a side view of the invention.
Fig. 2 is a plan view of the same.
Fig. 3 is a section on the line 3—3 Fig. 2.
Fig. 4 is a detail perspective view of one of the detachable units.

- 20 Fig. 5 is a section on the line 5—5, Fig. 3.
Fig. 6 is a detail perspective view of a cover plate.

The invention has relation to autographic registers for use in registering or recording memorandums and sales in mercantile and other transactions, and it consists in the novel construction and combinations of parts, as hereinafter set forth.

In the accompanying drawings, illustrating the invention, the numeral 2 designates a frame or casing, consisting of sides 3, held together by transverse braces 4, said sides having central perforations 5, pivotally engaging a rod 6 carried by standards 35 7, said standards located upon a base 8.

Fitting within the casing is a detachable frame 9, consisting of a platform plate 10, provided with inward extensions 11, 11', carrying a rod 12 and a rotary spindle 13, 40 designed respectively to receive the paper supply or feed roll 14 and for winding of the paper to constitute the record roll 15, the paper passing from the supply roll outwardly longitudinally over the platform plate, the upper sheet or sheets of paper 16 passing then over a roller 17, carried by said frame and located at the forward end of the platform plate and carrying an annular series of short pointed teeth or projections 18 for engagement with the said outer sheet or sheets, to insure a positive feed thereof without back slip, and thence out of the casing. The lower sheet or sheets of paper 19 also pass over this roller, in engagement with the points thereof, and thence

inwardly to the record spindle, to which they are made fast at the end, for winding.

In order to insure that the paper sheets shall be pressed into engagement with the points of the feed roller, a pressure device 60 is employed, consisting preferably of a rubber roller 20, having bearings in upper extensions 20' of the frame 9 and located immediately over the feed roller and usually in contact therewith, the teeth of the feed 65 roller usually engaging the rubber of the roller through an annular series of perforations, formed therein by the teeth themselves.

Provision is made for carbon impressions, 70 usually by a longitudinal carbon supply rod 21, engaging lateral extensions 21' at one side of said frame 9, the carbon sheet or sheets passing from said rod transversely over the platform plate, between the paper sheets passing longitudinally over the platform plate, the carbon sheet being at its free end wound around a longitudinal roller 22, engaging lateral extensions 22' at the other side of the frame 9. Upon turning of 75 the roller 22, a new supply of carbon paper will be fed between the paper sheets, and the worn carbon wound upon said roller.

The frame 9, carrying the supply roll of paper, with the paper sheets therefrom suitably adjusted over the platform plate, in engagement with the teeth of the feed roller, and with the record sheet in engagement at its end with the record spindle, and the carbon sheets suitably adjusted in position, is 80 slidably fitted into the open top of the casing, in engagement, through the medium of the lateral extensions 21' 22', with guides 23 of said casing, after which a cover plate 24 is fitted over the platform plate, said 85 cover plate having at one end a thicker portion 25, wherein is located a transverse slot 26, between upper and lower horizontal end bars 26', closely adjacent to the feed roller, so that when the paper sheet is fed 90 therefrom it will at once pass into engagement with this slot, and out of the machine.

The frame 9 is provided with upward projecting lugs engaging the cover plate, the platform plate being thereby spaced apart 105 from the cover plate by an interval wherein the paper passes over the platform plate, said lugs usually forming part of the lateral extensions 21', 22', and of rear guide lugs 23'.

This cover plate is provided with an opening 24', to expose the platform plate, and with a transverse opening 27, wherein fit the rubber roller and the frame extensions in 5 which said rubber roller has rotary bearings. The cover plate is also provided with studs 28, engaging seats 28' of the frame, to secure proper alinement. An open-end opening 31 of this plate allows the milled handle 32 of 10 the carbon feed roller to project without the casing, for manipulation.

The four cover plates abut at the ends, and the plates close respectively the open ends of the openings 31 of the adjacent 15 plates.

The carbon supply rod is also provided with a shorter milled handle 21', located within the casing. The record spindle 13 is provided with a crank handle 33, and the 20 supply rod 12 is provided with a milled handle 33', which fit respectively within 25 open-end slots 34, 34' of the casing. The cover plate being placed in position, screws 35, having milled heads, are engaged with threaded perforations 30 of the casing, to 30 secure the plate in position.

Means are provided to adjustably check the movement of the paper supply roll, as may be required, consisting preferably of a 30 threaded end 36 of the supply rod, engaging a threaded perforation 36' of an inward extension 11 of the frame, the extensions 11 being made of spring character, so that when the milled handle of the supply rod is turned 35 the shoulder of said handle will bear against an extension and the extensions will be drawn toward each other into frictional engagement with the paper roll. This threaded engagement of the end of the supply rod also enables the supply rod to be 40 readily removed from the frame when a new supply roll is to be inserted in the machine.

Means are provided to detachably hold the record spindle 13 in the frame, consisting 45 usually of a head 37 of said spindle and a groove 38 behind said head, which is inserted through a perforation of an inward extension 11', a spring 39 of the frame engaging said groove, between said head and 50 the said extension. Upon release of the spring the spindle may be slid out endwise from its bearings in the frame extensions. This spindle is provided with means for fastening the end of the paper sheet thereto, 55 usually consisting of a flat side 40 and a rod spring 41, overlying said flat side and serving to press the end of the paper sheet thereagainst.

The carbon supply rod, upon which the 60 roll of carbon paper is placed, has releasable engagement with the frame 9, usually by means of a threaded end 42, engaging a threaded perforation of an extension 21' of said frame, the other end of said rod engaging a perforation of the other extension

21'. The carbon feed roller has also releasable engagement with the frame, preferably by means of a headed end 43, passing through a perforation of a lateral extension 22' of the frame 9, a spring 44 of said frame 70 engaging a groove of said rod behind said head, the other end of said roll passing through a perforation of the other extension 22'. The end of the carbon paper is made fast to said roll by means of a rod spring 46, 75 carried by the roll and engaging a longitudinal groove of the roll. A ratchet and pawl means 22' may be used to prevent the carbon feed roller from turning backwardly.

It is preferred to make the feed roller 17 of wood, and to have the pointed teeth thereof carried by a metal band 47, fitting in a groove of the roller and provided with depressions 48, respectively surrounding the teeth or in which the teeth are located. This feed roller is usually engaged with inclined open-end grooves 49 of the frame 9, the rubber roller being then secured in position above the feed roller, and through engagement with the teeth of the roller serving to 80 keep the feed roller in position.

A hand rest 50 is provided at the forward end of the machine, said rest being carried by a lateral arm 51, made fast to the pivot rod of the machine by suitable means, as a 95 split clamp device 52, having a screw 53 engaging the branches of the clamp and serving to force them into tight engagement with said rod. Means are provided to hold the rotary casing stationary with any face or 100 platform plate thereof uppermost, consisting preferably of a spring-pressed rod 54, carried by said lateral arm 51 and automatically engaging any one of four electric perforations 51' of the casing, corresponding to the 105 four sides thereof. By varying the adjustment of the clamp 52 upon the pivot rod, the inclination of the faces or platform plates of the machine may be varied as desired.

It is preferred to provide the casing with a plurality of faces, usually four, as shown, to provide for the entry and recording of sales of a number of different kinds or classes, each face being provided with a detachable 115 frame 9, carrying a paper supply roll, a record rod having the end of the paper fastened thereto, a platform plate over which the paper passes, a feed roller and an upper pressure roller between which the paper 120 is suitably adjusted, a carbon supply roll and a carbon roll upon which the worn carbon is wound, the carbon sheets being suitably adjusted between the paper sheets, said frame and the parts carried thereby 125 constituting a unit which may be conveniently handled and greatly facilitating the necessary adjustments of the paper and carbon.

When the record roll is complete, the 130

unit is detached from the machine, refilled and replaced in the machine. These units may be placed in the machine by an unskilled person, the register then being ready for use.

I claim:

1. In an autographic register, an open-top hollow casing, an inner frame detachably fitting in said casing and having a platform plate located at the top of the casing, a paper supply rod, a record spindle, a carbon supply rod, a carbon spindle carried by said frame and removable therewith and a cover plate detachably connected to the casing and overlying and having an opening therein to expose said platform plate.

2. In an autographic register, an open-top hollow casing, an inner frame detachably fitting in said casing and having a platform plate located at the top of the casing, a paper supply rod, a record spindle, a carbon supply rod and a carbon spindle carried by said frame and removable therewith, a supply roll mounted upon the paper supply rod, the paper sheets therefrom passing longitudinally over the platform plate and the lower sheet thence passing inwardly to the record spindle, and a supply roll mounted upon the carbon supply rod and the carbon therefrom passing transversely over the platform plate to the carbon spindle.

3. In an autographic register, an open-top hollow casing, an inner frame detachably fitting in said casing and having a platform plate located at the top of the casing, a paper supply rod and a record spindle carried by said frame, a feed roller and a pressure device located above said feed roller and coöperating therewith, also carried by said frame and a cover plate detachably connected to the casing and overlying and having an opening therein to expose said platform plate.

4. In an autographic register, an open-top hollow casing, an inner frame detachably fitting in said casing and having a platform plate located at the top of the casing, a paper supply rod and a record spindle carried by said frame, and a feed roller carrying an annular series of pointed teeth, and a soft rubber pressure device located above and coöperating with said feed roller, also carried by said frame, said pressure device having recesses therein formed by said teeth.

5. In an autographic register, an open-top hollow casing, an inner frame detachably fitting in said casing and having a platform plate located at the top of the casing, a paper supply rod and a record spindle carried by said frame, and a feed roller carrying an annular series of pointed teeth, and a soft rubber pressure roller located above and coöperating with said feed

roller, also carried by said frame, said roller having an annular series of recesses therein formed by said teeth.

6. In an autographic register, an open-top hollow casing, an inner frame detachably fitting in said casing and having a platform plate located at the top of the casing, inner extensions and lateral extensions, a paper supply rod and a record spindle carried by said inner extensions, and a carbon supply rod and a carbon spindle carried by said lateral extensions.

7. In an autographic register, an open-top hollow casing, an inner frame detachably fitting in said casing and having a platform plate located at the top of the casing, inner extensions and lateral extensions, a paper supply rod and a record spindle detachably engaging said inner extensions, and a carbon supply rod and a carbon spindle detachably engaging said lateral extensions.

8. In an autographic register, an open-top hollow casing, an inner frame detachably fitting in said casing and having a platform plate located at the top of the casing, a paper supply rod and a record spindle carried by said frame, and a cover plate detachably connected to the casing and overlying and having an opening therein to expose said platform plate.

9. In an autographic register, an open-top hollow casing having an open-end groove, an inner frame detachably fitting in said casing and having a platform plate located at the top of the casing, a paper supply rod and a record spindle carried by said frame, said record spindle having an operative end fitting in said open-end groove, and a cover plate detachably connected to the casing, covering in the open-end groove thereof and overlying and having an opening therein to expose said platform plate.

10. In an autographic register, an open-top hollow casing having open-end grooves, an inner frame detachably fitting in said casing and having a platform plate located at the top of the casing, a paper supply rod and a record spindle carried by said frame, said record spindle having a cranked end fitting in one of said grooves and said supply rod having a head fitting in the other of said grooves, and a cover plate detachably connected to the casing, covering in the open-end grooves therein and overlying and having an opening therein to expose said platform plate.

11. In an autographic register, an open-top hollow casing, an inner frame detachably fitting in said casing, having a platform plate located at the top of the casing and inner extensions, two of which are of spring character, a paper supply rod having a threaded end engaging a threaded perforation of one of the inner spring extensions and having a handle end bearing against

the other of the spring inner extensions to draw the extensions together, and a record spindle engaging the other of said extensions and having at one end an annular 5 groove, and a spring carried by the casing and releasably engaging said groove.

12. In an autographic register, an open-top hollow casing, an inner frame detachably fitting in said casing and having a 10 platform plate located at the top of the casing and lateral extensions, a paper supply rod and a record spindle carried by the casing, a carbon supply rod having a threaded end engaging a threaded perforation of one 15 of said extensions, the other end of said carbon supply rod and a carbon roller having slidable engagement with perforations of the others of said lateral extensions, and said carbon roller having at one end a groove and 20 a spring upon said frame releasably engaging said groove.

13. In an autographic register, an open-top hollow casing, an inner frame detachably fitting in said casing and having a platform plate located at the top of the casing, a 25 paper supply rod and a record spindle carried by said frame, a feed roller, and a pressure device located above and coöperating with said feed roller and also carried by said 30 frame, and a cover plate detachably connected to the casing and having openings therein to expose said platform plate and to receive said pressure device, said cover plate having at its forward end upper and lower 35 bars and a horizontal slot between said bars, located adjacent to said feed roller.

14. In an autographic register, a support, a hollow peripherally-open casing having opposite polygonal sides, provided with central perforations and eccentric perforations, a pivot rod carried by said support and engaging said central perforations, an arm having an adjustable connection with said pivot rod, a hand rest at the other end of said arm, means for holding said casing stationary, consisting of a spring-pressed pin carried by said arm and engaging said eccentric perforations, a plurality of inner frames detachably fitting in the peripheral opening of the casing and having platform plates located around the polygonal sides of the casing, a paper supply rod and a record spindle carried by each of said frames, and cover plates detachably connected to the casing and overlying and having openings therein 55 to expose said platform plates.

15. In an autographic register, an open-top hollow casing, an inner frame detachably fitting in said casing and having a platform plate, a paper supply rod and a record spindle carried by said frame, and a feed roller having pointed teeth and a soft rubber pressure device located above and coöperating with said feed roller, also carried by said frame, said pressure device having recesses therein formed by said teeth.

In testimony whereof I affix my signature, in presence of two witnesses.

ANDREW HELDRICH.
